ROTARY COMPRESSOR FOR REFRIGERATING APPARATUS

Rolf M. Smith, Dayton, Ohio, assignor to General Motors Corporation, Dayton, Ohio, a corporation of Delaware

Application March 31, 1936, Serial No. 71,869

6 Claims. (Cl. 230—149)

This invention relates to refrigerating apparatus and more particularly to refrigerant compressors and pumps.

Rotary pumps and compressors are now widely used for pumping liquids and gases including refrigerants. In such pumps a rotary member is ordinarily provided within the cylinder which describes a path which extends around the interior of the cylinder with a relatively small clearance. It has been customary to make this clearance uniform throughout the entire pumping or compression stroke regardless of the fact that the pressure differences vary considerably throughout the stroke and generally are at a low value at the beginning of the stroke and at a relatively high value beginning with the last two-thirds or three-fourths of the stroke. Therefore, if the pump had a relatively large amount of clearance the efficiency would be considerably reduced.

It is an object of my invention to adjust the clearance generally according to the local pressure differences which exist in such a pump.

It is another object of my invention to provide an improved method of and means for adjusting the clearance in the portion of the stroke where the higher pressure differences and the higher fluid density exist.

It is still another object of my invention to provide a two stage rotary compressor having the advantages of simplicity, ease of manufacture, and a minimum of parts.

In a two stage rotary compressor, it has also been customary to make the clearance in both stages uniform regardless of the fact that the pressure differences in the higher stage are greater and that leakage in the higher stage is a more serious consideration than in the lower stage.

It is an object of my invention to provide a rotary compressor of the two stage type in which the clearance in the higher stage is less than the clearance in the lower stage.

It is another object of my invention to provide an improved means and method for adjusting the clearance in the portions of rotary compressors which require greater accuracy in achieving a minimum clearance.

Further objects and advantages of the present invention will be apparent from the following description, reference being had to the accompanying drawings, wherein a preferred form of the present invention is clearly shown.

In the drawings:

Fig. 1 is a vertical sectional view taken along

the line 1—1 of Fig. 2 through a rotary refrigerant compressor embodying one form of my invention, together with a diagrammatic representation of the remainder of the refrigerating system;

Fig. 2 is a fragmentary sectional view taken along the line 2—2 of Fig. 1;

Fig. 3 is a fragmentary sectional view taken along the line 3—3 of Fig. 2;

Fig. 4 is an exaggerated diagrammatic view 10 showing the customary clearances provided in the stages of a two-stage rotary compressor; and

Fig. 5 is a view similar to Fig. 4 but with the clearances properly adjusted in an exaggerated form according to my invention.

Briefly, I have disclosed a sealed unit type of rotary refrigerant compressor having an eccentric roller type of rotor and a plurality of divider blocks positioned about 120° from each other, which divides the space between the rotor and its cylinder into two pumping chambers of which the lower pressure chamber extends through an arc of approximately 240° while the higher pressure chamber extends through an arc of approximately 120°. The low pressure chamber is provided with an inlet in the usual position adjacent one of the divider blocks and an outlet adjacent the other divider block provided with a flapper valve housed within the chamber which communicates with the inlet of the high pressure pumping chamber. The high pressure pumping chamber is likewise provided with an outlet and a flapper valve which permits the discharge of the compressed gas into the interior of the sealed unit.

The outlet from the sealed unit is through a hollow stationary shaft which serves to support the hollow rotary drive shaft. The compressed gas from this outlet is conducted to the plate type condenser where it is liquefied and forwarded to an evaporator means where it evaporates and is returned to the inlet of the large pumping chamber in vapor form.

The wall of the cylinder is provided with a lateral screw thread adjusting means for adjusting 45 its position laterally so that the clearance in the high pressure chamber may be made less than that in the low pressure chamber. In order to do this conveniently, the screws which normally anchor the cylinder or the high pressure 50 portion thereof, may be loosened slightly and provided with a rather loose fit in the cylinder so that the clearance in the high pressure chamber may be readily adjusted to a desired fixed value.

Referring now more particularly to the drawings, there is shown a motor-compressor unit generally designated by the reference character 20 for compressing refrigerant and for forwarding the compressed refrigerant to a flat plate type condenser 22 where the compressed refrigerant is liquefied and forwarded through a conduit 24 under the control of an expansion control device 26 to an evaporating means 28 located within a compartment 30 containing a medium to be cooled. The refrigerant evaporates within the evaporating means and is returned to the inlet of the compressor through a return conduit 32. The operation of the motor-compressor unit is controlled by a snap acting switch 34 operated according to the temperature of a thermostatic bulb mounted upon the evaporating means and located in electrical series circuit relationship with the stator 36 of an electric driving motor 20 which includes the rotor 38.

The compressor includes an inverted outer cup shaped casing member 40 which has a lower flange or rim which receives a flanged bottom member 42 provided with a metal seal 44 between the extremities of the flanges. Between this inverted cup shaped member 40 and the bottom plate is a vertical hollow stationary shaft 46 which serves as the outlet for the compressed gas. A hollow drive shaft 48 is rotatably mounted upon the stationary vertical shaft 46 and carries the rotor at its upper end while at its lower end, it is provided with an eccentric portion 50 which has a roller 52 rotatably mounted thereon which, together with the eccentric portion 50, serves as the rotor or impeller of the compressor. This roller 52 revolves about the axis of the stationary shaft 46 within the cylindrical housing 54.

Beneath the cylinder 54 and the roller 52 is a hardened ground steel plate 56 which has beneath it a second plate 58 of somewhat softer metal which is welded or otherwise secured to the flat center portion of the bottom plate 42. The cylinder 54 is fastened to the plate 58 by cap or machine screws 60 which extend through relatively large holes in the cylinder. Above the cylinder 54 and the rotor 52 is provided a second plate 62 of hardened ground steel provided with a second plate 64 of softer steel above it. These two plates are fastened to the cylinder by the screws 66. Extending through gaps or slots in the wall of the cylinder 54 are the divider blocks 68 and 70 which are located 120° apart. These blocks divide the space between the roller 52 and the cylinder 54 into a large low pressure pumping chamber 72 which extends through an arc of nearly 240° and a small high pressure pumping chamber 74 which extends through an arc of nearly 120°.

An inlet opening 76 for the low pressure pumping chamber 72 is located immediately adjacent the divider block 70 in a clockwise direction therewith. This opening extends down through the plates 56, 58 and 42 and is provided with a threaded coupling member 78 upon the bottom of the sealed unit for connection with the return conduit 32. The outlet of this low pressure pumping chamber 72 is provided by an aperture 80 in the plate 62 which opening is provided with a hardened face member which has its upper flanged edge serving as a valve seat for a flapper discharge valve 82 located in a chamber 84 provided in the upper plate 64, which chamber is closed at its top by an additional plate member 86. This flapper valve is provided with a heavy steel guard member 88 which with the flap-

per valve is fastened to the plate 62 by screws at the fixed end. This guard member mounting serves to prevent excessively wide opening of the flapper valve and thus prevents it from being stressed excessively and thereby prevents it from breaking on account of fatigue stress. 5

This chamber 84 is located above the divider block 68 and has its inlet opening 80 upon the counterclockwise side of the divider block 68 while it has its outlet opening 88 within the plate 62 upon the opposite side of the divider block 68 leading directly into the inlet end of the smaller pumping chamber 74. At the opposite end of the small pumping chamber 74, there is provided a discharge opening and a flapper valve 92. It discharges into the interior of the sheet metal member 94 which surrounds the upper portion of the compressor. This sheet metal member in cooperation with the drive shaft 48 provides a space and a sort of a labyrinth path for separating the refrigerant from the oil or lubricant 96 provided in the bottom portion of a compressor. This casing also provides an anchor for the divider block springs 98 which extend into drilled recesses in each of the divider blocks 68 and 70 in order to hold the inner surface of the divider block against the roller 52. 15 20 25

The two sections of the cylindrical wall 54 are held together by the screws 66 and the top plates 62 and 64. This unit is held in place normally 30 by the cap or machine screws 60 which extend through rather large holes in the wall 54 so that the screws may be loosened slightly and the wall positioned in order to provide whatever clearance is desired. It has heretofore been customary 35 to maintain a uniform rotor clearance throughout the stroke of the rotor in a rotary compressor. There is, however, a greater tendency to leakage during the final portions of the stroke in a single-stage compressor and during the final 40 stages in a multi-stage compressor.

I propose to make this clearance less than in final stages of a single stage compressor, as well as in the final stage of a multi-stage compressor. This is illustrated diagrammatically in Figs. 4 45 and 5, wherein there is provided a cylindrical wall 110 provided with divider blocks 112 and 114. Within the cylinder is a rotor 116 mounted eccentrically upon the drive shaft 118. It will be seen that the clearance in the second stage pumping 50 chamber 120 is substantially the same as indicated by the dotted line 122 in the lower stage 124. According to my invention I adjust the position of the cylindrical wall 110 so that clearance at the high pressure pumping chamber 120 is less 55 than the clearance in the larger low pressure pumping chamber 124 as indicated by the dotted line 126. This naturally reduces leakage in the high pressure pumping chamber and has little effect upon the leakage in the low pressure pumping chamber because of its larger volume. 60

Thus, I propose to make the cylindrical wall adjustable so that the clearance may be readily adjustable to obtain improved performance of the compressor, particularly by reducing the 65 clearance in the higher pressure or pressure differential portions of the compressor. In addition to this, however, I have also provided a means for readily making this form of lateral adjustment conveniently and accurately. In 70 order to do this, I have provided a bracket 130 fastened to the flanged bottom plate 42. This bracket 130 rotatably supports the head 132 of an adjusting screw 134 which is threaded into a threaded aperture 136 extending in a radial direc- 75

tion into the cylindrical wall 54. By turning this screw 134 in one direction or the other, with the screws 60 slightly loosened, the cylindrical outer wall may be moved to provide greater or less clearance as needed in the high pressure portions of the low pressure pumping chamber, as well as the high pressure pumping chamber.

In the form of invention shown in the drawings, there are at least two different ways in which this might be done. In the first place, it should be noted that the cylindrical wall 54 is divided into two wholly separate parts by the divider blocks 68 and 70 which are in the proportions of about 240° and 120°.

15 In one way, the adjustment is made before the application of the upper plates 62 and 64, and the larger or 240° part of the wall 54 is anchored concentrically with the vertical stationary shaft 42. The 120° portion of the wall 54 is adjusted by the screw 134 to the desired clearance independently and without any reference to the clearance or location of the 240° portion of the wall 54. The 120° portion is then fastened in place permanently by screws 60 and divider blocks of the proper size are provided between the gaps in the cylindrical wall 54. This may be done by selective assembling. Thereafter, the upper plates 62 and 64 are fastened in place.

The second way may be used where it is desired to adjust the clearance by placing the entire cylindrical wall including the 120° and the 240° parts eccentrically of the stationary vertical shaft 46. To do this the two parts may be first assembled concentrically and then held together by fastening the upper plates 62 and 64 by the screws 66. Then this assembly may be adjusted to an eccentric position with the desired clearance in the second stage obtained by the adjustment of the screw 134.

40 In a single stage compressor, the cylindrical wall is in one horseshoe shaped piece and this may be readily adjusted eccentrically either before or after the application of the top plates 62 and 64 by a screw adjustment like that provided by the screw 134. After the adjustment is obtained the wall is permanently fastened in place. However, it is preferred to do this before the plates 62 and 64 are applied.

It is deemed most desirable, however, to adjust the cylindrical wall 54 so as to maintain a predetermined clearance in the high pressure pumping chamber and in the final portion of the low pressure pumping chamber and to permit the manufacturing variations to occur in the low pressure portion of the first stage pumping chamber. After the desired adjustment is obtained, a lock nut 138 upon the screw 134 may be tightened to hold the adjustment and thereafter the screws 60 may be tightened to fix the cylindrical wall in place with respect to the axis of the drive shaft 48 so as to preserve the clearance to which the compressor has been adjusted. After this position has been fixed, if desired, the screw 134 as well as the lock nut may be removed, thus making use of this feature somewhat as a fixture. This provides a very simple inexpensive means for obtaining the clearance desired.

While the form of embodiment of the invention as herein disclosed, constitutes a preferred form, it is to be understood that other forms might be adopted, all coming within the scope of the claims which follow.

What is claimed is as follows:

75 1. A rotary pump including a pumping cham-

ber wall, an impeller mounted within the chamber wall, means for revolving the impeller eccentrically along the chamber wall, a plurality of unsymmetrically positioned means with respect to the pumping chamber wall for providing a plurality of seals between the pumping chamber wall and the impeller to provide a plurality of pumping chambers of different size, a section of the pumping chamber wall between two of the sealing means having a lesser clearance between said section and the most eccentric portion of the impeller than between other portions of the wall and said most eccentric portion.

2. A rotary pump including a pumping chamber wall, an impeller mounted within the chamber wall, means for revolving the impeller eccentrically along the chamber wall, a plurality of unsymmetrically positioned means with respect to the pumping chamber wall for providing a plurality of seals between the pumping chamber wall and the impeller to provide a plurality of pumping chambers of different size, a section of the pumping chamber wall between two of the sealing means being a separate piece from the remainder of the wall and being movable independently from the remainder of the pumping chamber wall.

3. An eccentric type rotary pump including a pumping chamber wall, an impeller mounted within the chamber wall, means for revolving the impeller along the chamber wall, a plurality of divider blocks providing a plurality of seals between the pumping chamber wall and the impeller, said divider blocks being unsymmetrically positioned to provide pumping chambers of different size, said divider blocks being prevented from rotation with the impeller, a section of said chamber wall between two of the blocks being movable independently of the remainder of the chamber wall.

4. An eccentric type rotary pump including a pumping chamber wall, an impeller mounted within the chamber wall, means for revolving the impeller along the chamber wall, a plurality of divider blocks providing a plurality of seals between the pumping chamber wall and the impeller, said divider blocks being unsymmetrically positioned to provide pumping chambers of different size, said divider blocks being prevented from rotation with the impeller, a section of said chamber wall between two of the blocks being a separate piece from the remainder of the wall, said section having a lesser clearance with respect to the impeller than the remainder of the chamber wall.

5. An eccentric type rotary pump including a pumping chamber wall, an impeller mounted within the chamber wall, means for revolving the impeller along the chamber wall, a plurality of divider blocks providing a plurality of seals between the pumping chamber wall and the impeller, said divider blocks being unsymmetrically positioned to provide pumping chambers of different size, said divider blocks being prevented from rotation with the impeller, a section of said chamber wall between two of the blocks being movable independently of the remainder of the chamber wall, and adjusting means for moving said section toward and away from said impeller to change the clearance between said section and the impeller independently of other portions of the chamber wall.

6. A rotary pump including a pumping cham-

ber wall, an impeller mounted within the chamber wall, means for revolving the impeller along the chamber wall, and means prevented from rotation with the impeller for providing a seal between the impeller and the wall, said chamber wall being provided with a lesser clearance between the most eccentric portion of the impeller

and a portion of the wall extending upon one side of said seal means than is the clearance between said eccentric portion and a portion of the wall adjacent the other side of the seal means.

ROLF M. SMITH.
